SINGLE LEVER LAVATORY FAUCET

Aaron A. Staat, Edgewood, and Robert A. Staat, Ludlow,
Ky., and Merrit Nelson, Grand Rapids, Mich., assignors
to Bal-Cam, Inc., Cincinnati, Ohio, a corporation of
Ohio

Filed May 6, 1964, Ser. No. 79,846

Term of patent 14 years

(Cl. D91—3)

FIG. 1

FIG. 1 is a perspective view showing the front and left side of a single lever lavatory faucet embodying our new design.

FIG. 2 is a side view of the right side thereof.

FIG. 3 is a top plan view of FIG. 2.

We claim:

The ornamental design for a single lever lavatory faucet, as shown.
